UNITED STATES PATENT OFFICE

THOMAS L. HIBBARD, OF BIRMINGHAM, MICHIGAN, ASSIGNOR TO TERNSTEDT MANUFACTURING COMPANY, OF DETROIT, MICHIGAN, A CORPORATION OF MICHIGAN

DESIGN FOR AN AUTOMOBILE RADIATOR ORNAMENT OR SIMILAR ARTICLE

Application filed February 27, 1933. Serial No. 47,340. Term of patent 7 years.

To all whom it may concern:

Be it known that I, THOMAS L. HIBBARD, a citizen of the United States of America, residing at 540 Hawthorne Road, Birmingham, in the county of Oakland and State of Michigan, have invented a new, original, and ornamental Design for an Automobile Radiator Ornament or Similar Article, of which the following is a specification, reference being made to the accompanying drawing, forming part thereof.

Fig. 1 is a side elevation of an automobile radiator ornament or similar article, showing my new design.

Fig. 2 is a plan view of the same.

Fig. 3 is a front elevation of the same.

I claim:

The ornamental design for an automobile radiator ornament or similar article substantially as shown.

THOMAS L. HIBBARD.
